(51) LOC (10) Cl. **14-03**

(57) **CLAIM**

(52) U.S. Cl.

I claim the ornamental design for curved folded medical monopole antenna, as shown and described.

USPC **D14/230**

DESCRIPTION

(58) **Field of Classification Search**

USPC D14/138, 230, 231, 232, 233, 234, 235,
D14/236, 237, 238, 238.1, 299, 358;
D13/175, 182

CPC G01R 29/10; G01S 2013/0245; G01S
2013/0254; G01S 2013/0263; G01S
7/4026; G05B 2219/45001; G06K

H01C 1/088

FIG. 1 is a perspective view of a curved folded medical monopole antenna according to the invention.

See application file for complete search history.

FIG. 2 is a top plan view of the curved folded medical monopole antenna depicted in FIG. 1.

D673,535 S * 1/2013 Ko D14/230

FIG. 5 is another end elevation view of the curved folded medical monopole antenna depicted in FIG. 1.

FIG. 6 is a side elevation view of the curved folded medical monopole antenna depicted in FIG. 1; and,

FIG. 7 is another side elevation view of the curved folded medical monopole antenna depicted in FIG. 1.

The broken lines illustrate portions of the curved folded medical monopole antenna which form no part of the claimed invention.
